UNITED STATES PATENT OFFICE.

GEORGE KALTENECKER, OF HAMBURG, GERMANY.

UMBRELLA.

SPECIFICATION forming part of Letters Patent No. 735,776, dated August 11, 1903.

Application filed March 26, 1903. Serial No. 149,677. (No model.)

To all whom it may concern:

Be it known that I, GEORGE KALTENECKER, a subject of the Emperor of Germany, residing at Hamburg, Germany, have invented certain new and useful Improvements in Umbrellas, of which the following is a specification.

This invention relates more particularly to umbrellas which open automatically; and its objects are to provide such a device that will be simple in construction and of light weight.

In the accompanying drawings, Figure 1 is a longitudinal sectional view. Fig. 2 is a cross-sectional view showing the rib connections. Fig. 3 is a view showing the ratchet-and-pawl mechanism in released position, and Fig. 4 is a cross-sectional view showing the operating-lever.

A hollow stick *a* carries the ribs *b*, which are pivoted at *c* to suitable bearings or lugs on the stick. The ribs *b* are provided at their inner ends with toothed sectors *d*, which engage with a circular rack *e*, which is guided in the stick *a* by a piston *g* and normally urged upward by a spring *h*, which is fixed thereto and to the end of the stick. The stick is strengthened by a sleeve *f* along the section which is cut through for the sectors on the ribs. A rod *i* connects the rack *e* with a ratchet-bar *k* near the handle. This ratchet-bar may be actuated by a pawl *r* on a lever *o*, pivoted at *p* to a lug *q* on the handle. A spring-dog *s* is also arranged to engage the ratchet *k* and to be engaged or released by the pawl *r*. The spring-dog *s* is released from engagement with the ratchet *k* by being pressed outward by the pawl *r* when the latter is raised beyond its normal throw for operating the ratchet. In order to allow a slight transverse movement, the bar *k* is supported between

two pins *n* on one side and a spring *m* on the other side.

The operation of the device is as follows: The umbrella being closed, the lever *o* is successively raised and then pressed down to the position indicated at *o'*, Fig. 1. This causes the pawl to pull down the ratchet-bar, rod *i*, and rack *e*, and the latter in turn causes the segments to swing the ribs out and up. The umbrella is closed by raising the lever *o* to the position shown at *o''*, Fig. 3. This releases the dog *s* and allows the spring *h* to pull the rack up, and consequently swing the ribs down.

Having thus described my invention, what I claim, and desire to secure by Letters Patent, is—

1. In an umbrella, the combination with a hollow stick, of a slidable rack in said stick, pivoted ribs having toothed sectors engaging said rack and means for reciprocating said rack to swing said ribs.

2. In an umbrella, the combination of a hollow stick, ribs pivoted to said stick having toothed segments projecting into said stick, a rack engaging said segments, a spring secured to said rack and the tip of said stick, a rod from said rack, a ratchet-bar adjacent to the handle with which said rod connects, a pivoted lever having a pawl adapted to engage said ratchet-bar, and a spring-dog engaging said ratchet and adapted to be released by said pawl.

In testimony whereof I have affixed my signature in presence of two witnesses.

GEORGE KALTENECKER.
